(57) CLAIM

The ornamental design for a vehicle grill, as shown and described.

DESCRIPTION

FIG. 2 is a right side view in elevation of the vehicle grill shown in FIG. 1 with an exploded view of the mounting housing shown in broken lines for illustrative purposes only so that it forms no part of the claimed design;

FIG. 3 is a front view in elevation of the vehicle grill shown in FIG. 1;

FIG. 4 is a rear view in elevation of the vehicle grill shown in FIG. 1;

FIG. 5 is a left view in elevation of the vehicle grill shown in FIG. 1 with an exploded view of the mounting housing shown in broken lines for illustrative purposes only so that it forms no part of the claimed design;

FIG. 6 is a top plan view of the vehicle grill shown in FIG. 1 with an exploded view of the mounting housing shown in broken lines for illustrative purposes only so that it forms no part of the claimed design; and,
